UNITED STATES PATENT OFFICE.

THOMAS E. MADDUX, OF GOLDBAR, WASHINGTON.

TACKLE-BLOCK.

SPECIFICATION forming part of Letters Patent No. 733,239, dated July 7, 1903.

Application filed November 1, 1902. Serial No. 129,664. (No model.)

To all whom it may concern:

Be it known that I, THOMAS E. MADDUX, a citizen of the United States, and a resident of Goldbar, in the county of Snohomish and 5 State of Washington, have invented a new and Improved Tackle-Block, of which the following is a full, clear, and exact description.

This invention relates to single-sheave blocks, and particularly to a class known as 10 "snatch-blocks," used to change the direction of pulling strain of a draft-cable while hauling logs or timber overland from one point to another.

The object of my invention is to provide a 15 tackle-block of the class indicated with novel details of construction that adapt it for the free reception of the tackle rope or cable at any point between the ends of the latter, afford a very light, strong, durable, and inexpensive block which permits the sheave to 20 be readily removed, provides a substantial removable pintle-bolt for the support of the sheave, and adapts said bolt to hold one of the hinged side walls of the shell of the block 25 in closed adjustment, but permits its convenient release as occasion may require.

The invention consists in the novel construction and combination of parts, as is hereinafter described, and defined in the appended 30 claims.

Reference is to be had to the accompanying drawings, forming a part of this specification, in which similar characters of reference indicate corresponding parts in all the figures.

Figure 1 is a side view of the improved 35 tackle-block in closed condition. Fig. 2 is a transverse sectional view substantially on the line 2-2 in Fig. 1; and Fig. 3 is a partly sectional view of the block, showing the parts in 40 open adjustment.

The shell of the block consists of two flat side plates or cheeks 5 5^a, having a substantially ovate form on their edges, as shown in Fig. 1. Upon each side plate or cheek a strap 6 is secured by rivets, these straps of like 45 form extending lengthwise of the side plates or cheeks. Two hinge-leaves 6^a are formed on the upper end or head portion of each strap 6, said hinge-leaves being spaced apart 50 at the transverse center of said strap for the reception of a leaf 7^a on a corresponding end of a yoke-bar 7.

As shown, the yoke-bar 7 consists of a metal block having a leaf 7^a formed on each end, the thickness of said leaves adapting them 55 to respectively fit between a pair of the leaves 6^a, as before mentioned, and be thereon pivoted by a rivet-bolt 8, neatly fitted in central aligned perforations in each pair of joint-leaves 6^a and the leaf 7^a, which is inserted 60 between them.

At the longitudinal center of the yoke-bar 7 an eyebolt 9 is swivel-connected thereto by means of the loosely-fitted shank 9^a thereon, which is passed down through a perforation 65 in the bar and held to turn therein by riveting the projecting lower end, so as to form a radial flange thereon, as shown in Fig. 2. A grooved sheave-wheel 10 is provided, which is centrally perforated to receive the cylindrical body of the pivot-bolt 11.

The pivot-bolt is formed at one end with a square head 11^a of suitable dimensions, and from said head extends the cylindrical body 11, which is loosely inserted within the perforation of the sheave 10.

The bolt-body is reduced in diameter, so as to pass neatly through a central perforation in the side plate or cheek 5 and strap 6, toward which said bolt projects, and to permit a free 80 rotation of the sheave 10 on the bolt-body the shoulder *a*, where the bolt-body is diametrically reduced, bears on the side plate 5, so as to afford space between the head 11^a and said side plate sufficient in width to allow a free 85 rotation of the sheave 10 when the bolt is held in place on said plate and strap. The end portion of the bolt is extended beyond the strap, through which it passes, and is threaded for the reception of a nut 12, which when 90 screwed on the bolt so as to impinge forcibly upon the strap 6 serves to secure the bolt in place on the side plate or cheek 5 and strap 6.

A square orifice *b* is formed in the center of the strap 6 and the side plate or cheek 5^a, opposite the side plate and strap, whereon the bolt is firmly secured, and said angular orifice is so relatively positioned that it will freely receive the head 11^a when the latter has its sides disposed parallel with corresponding 100 sides of the orifice, it being understood that the bolt-head is slightly smaller than the orifice it occupies.

The bolt-head 11^a projects sufficiently out-

side of the side plate 5^a and the strap thereon to permit the formation of a perforation c therein that is adjacent to the outer surface of the strap on the plate 5^a when said strap 5 and plate are fully folded over the head so as to dispose the plate or cheek in loose contact with the adjacent side of the sheave 10.

A pin or preferably a split key, such as 13, (shown in Figs. 1 and 3,) is passed for a portion of its length through the perforation c when the side plate 5^a is fully folded over the bolt-head 11^a, and then the two members of said key are spaced apart, which removably secures the key in place.

15 To prevent the loss of the key, a small chain 14 or other available flexible connection is connected by one end to the bow end of the key and at the opposite end is secured upon the strap 6 on the side plate 5^a, the chain having sufficient length to permit the free insertion of the key 13, as before explained.

In the head 11^a and the body of the pivot-bolt 11 an oil-passage d is formed, as shown in Fig. 2, this passage enabling the free lubrication of the sheave 10 and the body of the pivot-bolt as may be necessary to insure the free working of the sheave on the pivot and also between the sides of the wheel and plates or cheeks 5^a.

20 30 It will be seen that the application of the snatch-block upon a draft-cable to change the direction of pull of the latter at any point between its ends may be readily made by the removal of the key 13, which will permit the side plate 5^a to be swung laterally and the yoke-bar 7 rocked on the strap 6, fixed on the side plate 5, which will freely expose the upper edge of the sheave 10 for the reception of the cable. (Not shown.)

40 45 As the split key 13 may be quickly removed by pulling upon the chain 14, it will be evident that when this is done the release of the cable from the block may be expeditiously effected and the cable removed by simply pulling the block sidewise, so as to press the cable against the released side plate 5^a, which will swing the latter outwardly into the position represented in Fig. 3.

It will be seen that the position of the yoke-bar 7 and the secured pivotal attachment thereon of the side plates 5 5^a by means of the straps 6 6, having hinge-leaves 6^a and the riveted pivots 8, that engage said ears, together with the ends of the yoke-bar, affords a very reliable means for opening the block, as already described, this being one feature of the improvement.

The provision of the removable headed pivot-bolt 11, which connects the sheave 10 with the side plate 5 in a manner that permits the free rotation of the sheave-wheel on said bolt-body, is another detail of the invention.

60 65 The provision of a shoulder a on the pivot-bolt 11 at the base of the thread thereon and which seats upon the side plate 5 when the nut 12 is forcibly drawn against the strap 6

affords a very reliable connection for the pivot-bolt with the side plate 5, so that the sheave is carried by the bolt and remains loosely supported on said bolt close to the side plate 7^a without regard to the relative position of the other side plate 5^a. This is another novel detail of the invention.

It will be seen that the formation of the angular head 11^a on the pivot-bolt 11 and the engagement of said head by the side plate 5^a and strap 6 when the head is passed through the angular perforation in the plate and strap adapts the latter to hold the pin from turning or becoming loose on the side plate 5.

In case the body of the pivot-bolt 11 is rendered untrue where it is most forcibly pressed upon by the sheave 10, which obviously is the side of the bolt nearest the yoke-bar 7, the pivot-bolt may be turned one-fourth of a revolution by applying a wrench to the head 11^a after slackening the nut 12, which will present a true surface of the bolt-body for engagement with the sheave at the point where the greatest wear is.

40 45 After the head 11^a of the bolt is turned as described it will be adapted to receive the side plate 5^a and the strap 6, having the angular perforation therethrough, and when so adjusted the bolt should be firmly secured on the side plate 5 by a proper adjustment of the nut 12.

It will be seen that as the head 11^a of the bolt is four-sided it may receive three successive adjustments after wear on the pivot-bolt 11^a body renders this change of position necessary. This provision is also a novel feature of the improved snatch-block.

Having thus described my invention, I claim as new and desire to secure by Letters Patent—

1. In a tackle-block, the combination of a cheek-plate movable relatively to the swivel-bar, a wheel rotatably secured thereto, and a second movable cheek-plate adapted to be brought into parallelism with the wheel-carrying plate, the construction being such that the wheel will be interposed between the movable plates, substantially as set forth.

2. In a tackle-block, the combination of two cheek-plates, pivoted to be movable outward relatively to the swivel-bar, a wheel carried by one of said cheek-plates, and means for locking the plates in approximately a position of parallelism, substantially as set forth.

3. In a tackle-block, the combination of a swiveled bar, a swinging cheek-plate pivoted to said bar, a wheel, a second swinging cheek-plate pivoted to the swiveled bar, and means passing through the two cheek-plates and the wheel for locking said plates in parallelism and permitting the wheel to be revolved between said plates, substantially as set forth.

4. In a tackle-block, the combination of a swiveled bar, two cheek-plates pivoted to said bar in such manner that the plates may be moved outward relative to each other or

brought into parallelism, a grooved wheel, and a bolt passing through the cheek-plates and the wheel, the construction being such that the plate will be locked in parallelism 5 and the grooved wheel may revolve freely between said plates, substantially as set forth.

5. A tackle-block comprising two cheek-plates, a strap on each of said cheek-plates, a yoke-bar hinged by its ends on each strap, a 10 swiveled eyebolt mounted on the yoke-bar, a pivot-bolt securable on one of the cheek-plates and one of the straps, a sheave-wheel rotatable on the pivot-bolt, said bolt having an angular head adapted to pass through a mating 15 orifice in either cheek-plate and strap, and means for detachably holding said cheek-plate and strap folded over the end of the pivot-bolt, substantially as set forth.

6. A tackle-block comprising two cheek-20 plates, a strap secured on each cheek-plate, said straps having hinged leaves at their upper ends, a yoke-bar, the ends of the yoke-bar having hinged engagement with the straps on the cheek-plates, a pivot-bolt threaded on one 25 end and shouldered on said end, such end passing through a perforation in one of the cheek-plates and one of the straps, a bolt having an angular head, the other cheek-plate and strap having a mating angular perforation 30 wherein the bolt-head firmly fits, and means for holding the cheek-plate and strap folded over the bolt, substantially as set forth.

7. In a device of the character described, the yoke-bar, the cheek-plates and straps therein 35 hinged upon the yoke-bar, the pivot-bolt held on one of the cheek-plates by a nut, said bolt having a square head, the other cheek-plate and strap having a square opening wherein the head of the bolt loosely fits, and a split 40 key adapted to pass through a transverse per-

foration in the head of the bolt for holding such cheek-plate upon said head.

8. In a tackle-block, the combination of two cheek-plates, pivoted to be movable outward, a horizontally - disposed, wheel - supporting 45 member carried by one of said cheek-plates, a wheel carried by said member, and means engaging with the aforesaid member for locking the cheek-plates in approximately a position of parallelism, substantially as set forth. 50

9. In a tackle-block, the combination of a swiveled bar, a swinging cheek-plate pivoted to said bar, a horizontally-disposed wheel-supporting member carried by the aforesaid cheek-plate, a second swinging cheek-plate 55 pivoted to the swiveled bar, and locking means passing through the wheel-supporting member adjacent to the outer surface of one of said cheek-plates for locking the said cheek-plates in parallelism, substantially as set 60 forth.

10. In a tackle-block, the combination of a swiveled bar, two cheek-plates pivoted to said bar in such manner that the plates may be swung outward relative to each other or 65 brought into parallelism, a bolt passing through the cheek-plates, a grooved wheel supported on said bolt between the plates, and a locking-pin adapted to pass through said bolt, the construction being such that the 70 plates will be locked in parallelism and the grooved wheels may revolve freely through said plates, substantially as set forth.

In testimony whereof I have signed my name to this specification in the presence of 75 two subscribing witnesses.
